UNITED STATES PATENT OFFICE

PETER JOSEPH KRAEMER, OF REGINA, SASKATCHEWAN, CANADA

BINDER

Application filed October 23, 1925. Serial No. 64,449.

This invention relates to improvements in binders, the general object of the invention being to provide endless chains with prongs thereon for carrying the grain from the platform to the binder table, thus eliminating the canvas belts, the rollers and the packers.

Another object of the invention is to arrange guide-ways for the chains which are located under the platform and tables so that the grain will not come in contact with said chains, the spikes on the chains projecting through slots in the platform and tables.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view partly in section showing the relation between the platform, elevator and binder table.

Figure 2 is a sectional view on line 2—2 of Figure 1 looking in the direction of the arrows.

Figure 3 is a sectional view on line 3—3 of Figure 1 looking in the direction of the arrows.

Figure 4 is a fragmentary longitudinal sectional view through the platform.

Figure 5 is a fragmentary transverse sectional view through the platform and showing the casing for the endless chain.

Figure 6 is a fragmentary plan view of the endless chain and one of the spikes.

Figure 7 is a view taken at a right angle to Figure 6.

Figure 8 is an enlarged fragmentary view showing the driving connection between the machine and the endless chains forming part of the elevator and binder table.

Figure 9 is a fragmentary view showing the pivoted arm and its association with one of the gears of the driving mechanism for said endless chains.

Figure 10 is a fragmentary plan view of Figure 9.

Figure 11 is a similar view of a slightly modified construction.

Figure 12 is a view showing the gear and the pivoted lever therefor.

In these views, 1 indicates the platform, 2 the elevator and 3 the binder table. As shown, the top elevator is taken off or omitted and a guide 4 is substituted which also acts to prevent the wind from blowing the grain passing up the remaining part of the elevator.

The platform, elevator and table are provided with slots 5 and they are covered with metal as shown at 6. A shaft 7 is placed at the junction of the platform and elevator and under the same, said shaft being supported in suitable bearings.

A plurality of sprockets are secured to this shaft and I prefer to make the shaft adjustable in its bearings. These sprockets are arranged in two sets, one set being shown at 8 and the other at 8'. A shaft 9 is placed at the front end of the platform and this shaft is provided with the sprockets 10 which are engaged by the endless chains 11, the chains also engaging the sprockets 8 on the shaft 7. These chains are provided with the spikes 12 which project through the slots 5 in the platform so as to draw the grain across the same to the elevator.

Here the grain is engaged by the spikes 13 on the endless chains 14 which pass over the sprockets 8' and the sprockets 15 on a shaft 16 which is located at the top of the elevator, the spikes passing through the slots 5 in the elevator.

The chains and spikes of the elevator are so arranged that the grain will be carried up the same and dropped upon the binder table, which is adjustably secured to the elevator by the grooves 17 and the slides 18.

The grain is carried across the binder table by the spikes 19 on the endless chains 20, which pass over the sprockets 21 on the shafts 22 and 23, the spikes passing through the slots 5 in said table. The shaft 23 is driven from a shaft 24, which is suitably supported and which is driven from a drive part of the binder, by means of the gears 25, 26 and 27, the gear 27 being located on a pivoted arm 28 which is adapted to be

100

engaged by the needle 28 which passes through a slot 29 in the table when a bundle is to be tied, so that the shafts will be disengaged and the feeding chains on the table will cease to operate. One shaft of each pair 5 can be adjusted to take up slack in the chains and channels 30 are located under the parts in which the chains operate. I prefer to form the spikes in two parts 31 and 32, each of 10 which engage a pin on a link 33 on a chain with the two parts bolted together as shown at 34. The drive shaft 7 and shaft 24 are driven by the chain 35 which is driven by a movable part of the binder. The channels 15 are reinforced by the strips 36 in order to prevent the chains from wearing them out.

From the foregoing it will be seen that the grain is carried from the knife to the binder table by the endless chains and their spikes 20 so that the use of canvas belts is rendered unnecessary. The parts are so arranged that the grain does not touch the chains so that there is no danger of the kernels being shattered as is the case where the packers are 25 used. This improved binder can be used in wet weather and early in the morning as by eliminating the canvas belts dew and moisture will not affect any part of the device.

It is thought from the foregoing description 30 that the advantages and novel features of my invention will be readily apparent.

I desire it to be understood that I may make changes in the construction and in the combination and arrangement of the several parts, 35 provided that such changes fall within the scope of the appended claim.

Having thus described my invention what I claim is:—

In a binder comprising a platform, elevator 40 and binder table provided with longitudinal slots, endless chains operating beneath said parts, spikes carried by each chain and operating through said slots, driving means for operating the chain beneath the binder table and including a train of gears, a pivoted 45 lever having a looped extremity slidably mounted on the shaft of one of said gears, a movable needle arranged beneath the table and adapted to project upwardly through a slot 50 therein, said lever being disposed in the path of movement of said needle and adapted to be engaged thereby to disconnect the last mentioned gear from the driving means, and thus automatically stop the endless chain of 55 the binder table while the bundle is being tied.

In testimony whereof I affix my signature.
PETER JOSEPH KRAEMER.
